[57] **CLAIM**

The ornamental design for the “rack for fishing lures”, as shown and described.

DESCRIPTION

FIG. 1 is a perspective view of a new design for a rack for fishing lures, the portions shown in ghost dot-dash lines for the purpose of environment only;

FIG. 2 is a top plan view with reference to FIG. 1;

FIG. 3 is a front elevational view;

FIG. 4 is a right side elevational view, the opposite side view being a mirror image thereof;

FIG. 5 is a rear elevational view; and,

FIG. 6 is a bottom view.
